(57) **CLAIM**

The ornamental design for a bottleneck connector, as shown and described.

DESCRIPTION

FIG. 1 is a front-top perspective view of a bottleneck connector showing my new design;

FIG. 2 is a front-bottom perspective view thereof;

FIG. 3 is a rear-top perspective view thereof;

FIG. 4 is a rear-bottom perspective view thereof;

FIG. 5 is a front elevational view thereof;

FIG. 6 is a rear elevational view thereof;

FIG. 7 is a left elevational view thereof;

FIG. 8 is a right elevational view thereof;

FIG. 9 is a top plan view thereof; and,

FIG. 10 is a bottom plan view thereof.

The broken lines shown in the figures are for the purpose of illustrating portions of the bottleneck connector and form no part of the claimed design.

1 Claim, 10 Drawing Sheets
